(57) **CLAIM**

The ornamental design for thermometer with static cling securing means, as shown and described.

DESCRIPTION

FIG. 1 is a top right isometric representation showing the new design;

FIG. 2 is a front view thereof;

FIG. 3 is a rear view thereof;

FIG. 4 is a left side view thereof; the right side view being a mirror image;

FIG. 5 is a top view thereof; and

FIG. 6 is bottom view.

FIGS. 7-9 are views of a second embodiment wherein:

FIG. 7 is a top right isometric representation;

FIG. 8 is a front view thereof, and

FIG. 9 is a back view thereof.

FIGS. 10-12 are views of a third embodiment wherein:

FIG. 10 is a right top isometric view thereof;

FIG. 11 is a front view thereof; and,

FIG. 12 is a back view thereof.
